UNITED STATES PATENT OFFICE.

HARRY M. KILPATRICK, OF ELMWOOD, ILLINOIS.

DESIGN FOR AN EMBLEM.

48,902.

Specification for Design.

Patented Apr. 18, 1916.

Application filed December 28, 1915. Serial No. 69,122. Term of patent 14 years.

To all whom it may concern:

Be it known that I, HARRY M. KILPATRICK, a citizen of the United States, and a resident of Elmwood, in the county of Peoria and State of Illinois, have invented a new, original, and ornamental Design for an Emblem, of which the following is a specification, reference being had to the accompanying drawing, forming a part thereof.

The figure is an elevation of an emblem showing my new design.

I claim:

The ornamental design for an emblem substantially as shown.

HARRY M. KILPATRICK.
